UNITED STATES PATENT OFFICE.

CLEMENT A. MAUS, OF INDIANAPOLIS, INDIANA.

LIQUID-COOLER.

SPECIFICATION forming part of Letters Patent No. 224,202, dated February 3, 1880.

Application filed September 9, 1879.

To all whom it may concern:

Be it known that I, CLEMENT A. MAUS, of Indianapolis, in the county of Marion and State of Indiana, have invented a new and useful Cooling Attachment for Barrels or Casks, of which the following is a specification, reference being had to the accompanying drawings.

My invention relates to a device for cooling the contents of a barrel or cask.

The object of my invention is to provide a cooling chamber or cylinder to contain ice, which is inserted in one head of a barrel or cask and made fast to the other head with perfectly tight joints, by means of which the contents of the cask or barrel may be kept cool.

My invention consists, mainly, in the construction and arrangement of a cooling-cylinder for holding ice, said cylinder having one end open and funnel-shaped, and fitting tightly in a tapering hole formed in one head of a barrel or cask, the other end closed and provided with a screw-threaded bolt, said bolt passing through and fitting snugly in a small hole formed in the other head of the barrel or cask.

My invention further consists of the new combination of my newly-constructed cooling-cylinder and a barrel or cask, by means of which the liquid contents of said barrel or cask may be cooled or kept cool, all of which will be hereinafter fully described and set forth.

In the accompanying drawings, in which like letters of reference in the different figures indicate like parts, Figure 1 represents an elevation of a barrel or cask, partially in section, showing the internal arrangement of parts fully. Fig. 2 is a view of the cooling-chamber detached from the barrel. Fig. 3 is a modified form of the cooling-chamber, and Figs. 4 and 5 are detached views of the upper cone-shaped casting.

A represents any ordinary liquor barrel or cask, mounted on the frame L, and provided with a faucet, P, in the usual manner. The upper head, D, is perforated by a large tapering hole, in which the conical part B' of the cooling-chamber B is inserted. The lower

head, H, is also perforated with a small hole, in which the bolt I of the lower end of the cooling-chamber B is inserted and made fast by the nut K below. The joint between the tapering part B' of the cooling-chamber and the head is made perfectly tight by a gasket or a close fit of the tapering part B' of the chamber. The joint between the screw I and head H may also be made tight in the same manner. The cooling-chamber B is cylindrical, and made of metal. Its upper part is made flaring or bell-mouthed, as shown at B', for the purpose of making a tight joint on its outside with the hole in the head D, and to receive the bung or stopper E on the inside. The extreme upper end is provided with a flange, C, to fit against the outside of the head D. It is obvious that an ordinary washer, C², may be used between the flange C and head D, and thus make a tight joint.

The lower end of the cooling-cylinder may be of any desired shape—that is, flat or rounded, as shown—and provided with a screw-bolt, I. The bolt I passes through the hole in the center of the lower head, and a washer, J, may be inserted between the inner side of the head and bottom of the cylinder B, or between the nut K and head H. Thus, when the nut K is screwed up tightly the cooling-cylinder is made fast and the joints at the top and bottom prevented from leaking, as described.

The cooling-chamber B B' is designed to be filled with ice and salt and replenished when desired. The cooling-chamber B is closed by the plug or stopper E, which is inserted in the tapering end B', as shown in Fig. 1.

Fig. 3 illustrates a modified construction of the cooling-chamber. The cylinder B, with flaring or bell-mouthed end B', is the same as in Fig. 2. The cast-metal tapering flanged ring B² is either smooth on its outer tapering side, as shown in Fig. 2, or corrugated, as shown at B⁴ in Fig. 4. This cast-metal ring is securely riveted and soldered to the flaring end B' of the cylinder, as shown in Fig. 3, or said ring may have a downward-projecting flange, B⁵, to be attached direct to the straight sides of the cylinder B, as shown in Fig. 5. The lower end of the cylinder is provided with a cast-metal end, B³, having the screw-threaded

bolt I at its base. The object of the cast-metal top and bottom B² B³ is to give the cylinder greater strength and permit the flaring part B² or B⁴ to be driven into the hole in the head 5 D and the tapering or curved part at the union of the screw I with the bottom B³ to be driven into the hole in the head H, and thus form tight joints when secured by the nut K. It is obvious that if the cylinder is made 10 wholly of thin metal it would not withstand the driving in of the bung E or removal of the same as well as with the cast-metal ends, as shown.

The cooling-chamber thus constructed may 15 be inserted or removed from a cask or barrel without injury to the coating of the barrel.

Prior to my invention various other forms 20 of cooling devices have been constructed and used in casks or barrels; but I am not aware of any which are constructed, arranged, and combined as in my invention.

What I claim as new, and desire to secure by Letters Patent, is—

1. The cooling-cylinder B, provided with an open tapered or bell-mouthed end, B', and a 25 closed end, with a screw, I, and nut K at its other end, combined with the barrel or cask A, as and for the purpose specified.

2. The cooling-cylinder B, provided with an open tapering or bell-mouthed end, B', and a 30 closed end, with screw I and nut K, as and for the purpose specified.

3. The cooling-cylinder B, provided with a tapering or bell-mouthed cast-metal end, B', provided with a screw-threaded bolt, I, as and 35 for the purpose specified.

4. The cast-metal bottom B³, provided with a screw-threaded bolt, I, combined with the cylinder B, as and for the purpose specified.

In testimony whereof I have signed my name 40 to this specification in the presence of two subscribing witnesses.

CLEMENT A. MAUS.
